UNITED STATES PATENT OFFICE.

EDWARD M. MOLLER, OF JERSEY CITY, NEW JERSEY.

STEP RAISING AND LOWERING DEVICE FOR RAILWAY-CARS.

1,163,359.

Specification of Letters Patent.

Patented Dec. 7, 1915.

Application filed September 18, 1915. Serial No. 51,329.

To all whom it may concern:

Be it known that I, EDWARD M. MOLLER, a citizen of the United States, residing at Jersey City, in the county of Hudson and State of New Jersey, have invented certain new and useful Improvements in Step Raising and Lowering Devices for Railway-Cars; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in railway cars; and, the invention has reference, more particularly, to a novel and simply-operated mechanism for raising and lowering the step or steps connected with the platform of a street-railway car.

The present invention has for its principal object to provide a simply-constructed and an effectively operating step-raising and lowering mechanism of the general construction hereinafter more fully set forth, and which is preferably operated from a vertical spindle which is actuated by the motorman or conductor of the car, at the same time that the vestibule door or doors of the car are closed or opened by such motorman or conductor.

Other objects of the present invention not at this time more particularly enumerated will be clearly understood from the following detailed description of the present invention.

With the various objects of the present invention in view, the said invention consists, primarily in the novel step-operating mechanism hereinafter more fully set forth; and, the invention consists, furthermore, in the novel arrangements and combinations of the various devices and parts, as well as in the details of the construction of the said parts, all of which will be described in the following specification, and then finally embodied in the clauses of the claims which are appended to and which form an essential part of the said specification.

The invention is clearly illustrated in the accompanying drawings, in which:

Figure 1 is a plan view of a portion of a

street-railway car and its platform, with a pair of folding steps and mechanism for operating said steps, the steps being represented in their lowered relation to the platform, and all showing one embodiment of the principles of the present invention. Fig. 2 is an elevation of the devices and parts shown in said Fig. 1, looking in the direction of the arrow *x*. Fig. 3 is a plan view, on an enlarged scale, of the left-hand end-portion of the devices and parts represented in said Figs. 1 and 2; and Fig. 4 is a similar view, also on an enlarged scale, of the centrally located portion of the devices and parts represented in said Figs. 1 and 2. Fig. 5 is a transverse vertical section, said section being taken on line 5—5 in said Fig. 1, looking in the direction of the arrow *y*, said view being also made on an enlarged scale; and Fig. 6 is a similar sectional representation of the same devices and parts illustrated in said Fig. 5, but showing the step raised, the parts of the step-raising and lowering mechanism in their relative positions when the step has thus been raised.

Similar characters of reference are employed in all the above described views, to indicate corresponding parts.

Referring now to the several figures of the drawings, the reference-character 1 indicates a fragmentary portion of the body of a street-railway car, which is provided at one or both of its ends with the usual platform, a fragmentary portion of which is here shown and is indicated by the reference-character 2.

The reference-characters 3 and 4 indicate the usual vertically disposed and rotatably arranged posts, mounted closely to the exit and inlet portions of the platform, and said posts having suitably mounted thereon the usual vestibule-doors or gates 5. The said platforms are suitably mounted upon the usual stringer or supporting beams 6 of the frame-work of the car. Suitably secured to the said stringers or beams 6, by means of bolts, as 7, or other suitable fastening means, are suitably formed angle-bars, as 8, to which are attached by means of bolts 9 and nuts 10, a pair of suitably-shaped outer brackets, as 11, and a pair of suitably-shaped inner brackets, as 12. The lower portions of said brackets 11 and 12 are

made with downwardly projecting elements or members, as 13, each element or member 13 having a forwardly extending portion, as 14, provided with a bearing 15. Oscillately mounted in said bearings 15 is a horizontally disposed shaft or shafts 16, said shaft or shafts having suitably affixed thereto, by means of pins 17, or other suitable fastening means, suitably-shaped step-
 10 carrying brackets, as 18 and 19, said brackets being suitably disposed in pairs, and each pair of said brackets 18 and 19, respectively carrying suitable steps 20 and 21. The said brackets 18 and 19 are also
 15 made with suitably disposed stop-members, as 22, which engage laterally extending projecting stops, as 23, with which the brackets 11 and 12 are provided, for limiting the downward movements of the steps 20 and
 20 21, and positively retaining said steps in horizontal positions, when lowered, as will be clearly evident.

Vertically disposed guards, as 24, may also be suitably affixed in said brackets 11
 25 and 12.

As shown, the lower portions of the previously mentioned door-carrying posts 3 and 4 are mounted in bearings 25 in the platform, and project suitably beneath the platform, the lower projecting portion of each post having suitably secured thereon, so as to oscillate with the post, an arm, as 26, each arm 26 being provided upon its free end-
 30 portion with a downwardly extending pin 35 26' carrying an antifriction roller 27. The previously-mentioned stringer or beam 6 has suitably secured thereto, in proper places, suitably constructed bearing brackets, as 28, each bracket carrying a pivot-pin 29, and
 35 connected with each pin 29 is a link 30. Each link is adapted to swing horizontally, and each link also has an enlarged portion, as 31, each enlarged portion being formed with an elongated opening 32 in which the
 40 anti-friction rollers 27 of the respective arms 26 are operatively arranged, as clearly indicated in Figs. 1 and 3 of the drawings. As shown more particularly in said Fig. 3, the said elongated openings 32 are bounded
 45 by the arc-shaped portions 33 and the straight portions 34, the arc-shaped portions 33 being parts of circles having their centers in the longitudinal central axes of the respective posts 4, so that the initial movements of the arms 26 and their rollers 27 will not affect or produce any movement of the links 30, until the said rollers 27 are brought into engagement with the straight portions 34, as will be clearly evident, and
 50 60 the purpose of which will be hereinafter more fully stated. The said enlarged portions 31 of the said links 30 are also provided with pairs of rearwardly projecting perforated lugs or ears 35, each pair of said
 65 lugs or ears being provided with a pin, as

36, upon which is loosely mounted between the said lugs or ears 35, the hub-like end-portion 38 of a connecting rod 37.

Pivottally connected with the opposite end-
 70 portions of the said connecting rods 37, by means of pins 39, are suitable crank-arms 40, said crank-arms being rigidly connected with a horizontally extending shaft or shafts, as 41, oscillately mounted in rear-
 75 wardly extending bearing-brackets, as 42, which are suitably secured by means of bolts 43 to the said angle-bars or beams 8, as clearly shown in the several figures of the drawings. Also suitably secured to the said shaft or shafts 41, and preferably adjust-
 80 ably mounted thereon by the split portions 45 and binding screws 46 and nuts 47, are other crank-arms or levers 44. Pivottally connected with the steps, as at 48, are the lower end-portions of rearwardly extending
 85 links 49, said links having their upper end-
 90 portions pivottally connected, as at 50, with the respective crank-arms or levers 44. A spring 51 is attached at one end to the pivot
 95 50 and at the other end to the platform 2, as at 52.

The purposes and operations of the various devices and parts described in the foregoing specification will be self-evident from an inspection of the several figures of the drawings, and, therefore, it is deemed unnecessary to further describe the manipulation and operations of the said devices and parts, except to state that when the door posts or rods 4 are operated, in the usual manner, for closing the vestibule-doors, the step-lowering and raising mechanism will not be operated until the anti-friction rollers 27 engage the straight portions 34 of the links 30, which will properly swing the 100 links and thereby at the proper time, that is when the doors are almost entirely closed, will operate the said step-raising mechanism, so that the steps are raised, with the help of the distended spring 51, only at the 110 time that the doors have been brought into their almost completely closed relation, or, vice versa, that the steps are completely lowered at the initial opening of the doors and before the doors have been finally swung 115 into their fully opened positions. The purpose of this is to guard against accidents to persons desiring to alight from or desiring to enter the car.

Of course I am aware that some changes 120 may be made in the general arrangements and combinations of the various devices and parts, as well as in the details of the constructions of the said parts, without departing from the scope of the present invention 125 as set forth in the foregoing specification, and as defined in the clauses of the claims which are appended to the said specification. Hence, I do not limit my present invention to the exact arrangements and combinations 130

of the said devices and parts as described in the said specification, nor do I confine myself to the exact details of the construction of the said parts as illustrated in the accompanying drawings.

I claim:—

1. In combination with an oscillatorily mounted door-carrying rod or post and a door mounted upon said rod or post, of a 10 step-operating mechanism, and means intermediate of said step-operating mechanism and said rod or post and actuated from said rod or post for actuating said step-operating mechanism simultaneously with the immediate closing or opening of the door, consisting of an arm mounted upon said door-carrying rod or post, a horizontally 15 swinging link, said link being provided with an elongated opening, said opening being bounded with an arc-shaped portion forming part of a circle having its center in the central longitudinal axis of said door-carrying rod or post, and said 20 opening being bounded also by a straight portion, a pin extending from said arm, a roller upon said pin, said roller extending into said elongated opening and being in engagement with said arc-shaped and said 25 straight portions, and a connecting rod between said link and the said shaft.
2. In combination with the platform of a car, an oscillatorily mounted door-carrying rod or post mounted upon said platform, said 30 rod or post having a portion extending beneath the said platform, and a door mounted upon said rod or post, a set of brackets mounted beneath said platform, a shaft mounted in said brackets, a folding step connected with said shaft, a second set of brackets also mounted beneath said platform, a shaft mounted in said last-mentioned brackets, a crank-arm connected with said last-mentioned shaft, a link pivotally connected 35 at one end with said crank-arm and at its other end with said step, and means intermediate of said last-mentioned shaft and said rod or post and actuated from said rod or post for actuating said last-mentioned shaft simultaneously with the immediate 40 closing or opening of the door, consisting of an arm mounted upon said door-carrying rod or post, a horizontally swinging link, means connected with said arm and in engagement with said last-mentioned link for intermittently swinging said link, and a connecting rod between said link and said last-mentioned shaft.
3. In combination with the platform of a 45 car, an oscillatorily mounted door-carrying rod or post mounted upon said platform, said rod or post having a portion extending beneath the said platform, and a door mounted upon said rod or post, a set of brackets mounted beneath said platform, a shaft 50 mounted in said brackets, a folding step connected with said shaft, a second set of brackets also mounted beneath said platform, a shaft mounted in said last-mentioned brackets, a crank-arm connected with said last-mentioned shaft, a link pivotally connected at one end with said crank-arm and at its other end with said step, and means intermediate of said last-mentioned shaft and said rod or post and actuated from said rod or post for actuating said last-mentioned shaft simultaneously with the immediate closing or opening of the door.
4. In combination with the platform of a 55 car, an oscillatorily mounted door-carrying rod or post mounted upon said platform, said rod or post having a portion extending beneath the said platform, and a door mounted upon said rod or post, a set of brackets mounted beneath said platform, a shaft mounted in said brackets, a folding step connected with said shaft, a second set of brackets also mounted beneath said platform, a shaft mounted in said last-mentioned brackets, a crank-arm connected with said last-mentioned shaft, a link pivotally connected at one end with said crank-arm and at its other end with said step, and means intermediate of said last-mentioned shaft and said rod or post and actuated from said rod or post for actuating said last-mentioned shaft simultaneously with the immediate closing or opening of the door.
5. In combination with the platform of a 60 car, an oscillatorily mounted door-carrying rod or post mounted upon said platform, said rod or post having a portion extending beneath the said platform, and a door mounted upon said rod or post, a set of brackets mounted beneath said platform, a shaft mounted in said brackets, a folding step connected with said shaft, a second set of brackets also mounted beneath said platform, a shaft mounted in said last-mentioned brackets, a crank-arm connected with said last-mentioned shaft, a link pivotally connected at one end with said crank-arm and at its other end with said step, and means intermediate of said last-mentioned shaft and said rod or post and actuated from said rod or post for actuating said last-mentioned shaft simultaneously with the immediate closing or opening of the door.

carrying brackets adapted to be brought into arresting engagement with said offsets, a step mounted upon said step-carrying brackets, a second set of brackets also mounted beneath said platform, a shaft mounted in said last-mentioned brackets, a crank-arm connected with said last-mentioned shaft, a link pivotally connected at one end with said crank-arm and at its other end with said step, and 5 means intermediate of said last-mentioned shaft and said rod or post and actuated from said rod or post for actuating said last-mentioned shaft simultaneously with the immediate 10 closing or opening of the door, consisting of an arm mounted upon said door-carrying rod or post, a horizontally swinging link, means connected with said arm and in engagement with said last-mentioned link for 15 intermittently swinging said link, and a connecting rod between said link and said last-mentioned shaft.

6. In combination with the platform of a car, an oscillatorily mounted door-carrying rod or post mounted upon said platform, 25 said rod or post having a portion extending beneath the said platform, and a door mounted upon said rod or post, a set of brackets mounted beneath said platform, said brackets being provided with stop-providing 30 offsets, a shaft mounted in said brackets, step-carrying brackets mounted upon said shaft, stop-members connected with said step-carrying brackets adapted to be brought into arresting engagement with said offsets, 35 a step mounted upon said step-carrying

brackets, a second set of brackets also mounted beneath said platform, a shaft mounted in said last-mentioned brackets, a crank-arm connected with said last-mentioned shaft, a link pivotally connected at one end with said crank-arm and at its other end with said step, and means intermediate of said last-mentioned shaft and said rod or post and actuated from said rod or post for actuating said last-mentioned shaft simultaneously with the immediate closing or opening of the door, consisting of an arm mounted upon said door-carrying rod or post, a horizontally swinging link, said link being provided with an elongated opening, 40 said opening being bounded with an arc-shaped portion forming part of a circle having its center in the central longitudinal axis of said door-carrying rod or post, and said opening being bounded also by a 45 straight-portion, a pin extending from said arm, a roller upon said pin, said roller extending into said elongated opening and being in engagement with said arc-shaped and said straight portions, and a connecting rod between said last-mentioned link and the 50 said last-mentioned shaft.

In testimony that I claim the invention set forth above I have hereunto set my hand this 16th day of September, 1915.

EDVARD M. MOLLER.
